UNITED STATES PATENT OFFICE

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS

COMBINED FILLING AND WARP STOP MOTION FOR LOOMS

Application filed August 1, 1927. Serial No. 209,653.

This invention relates to combined filling and warp stop motions and it is the general object of the invention to provide means whereby the actuating mechanism for the warp stop motion may be used to actuate the filling stop motion.

Patent No. 1,360,638 shows a form of knock-off motion which is generally employed in connection with my former Patent No. 1,265,112 wherein a rocking lever is effective at the time of warp fault to move the shipper handle to loom stopping position. It is an important object of my present invention to utilize this actuating lever to move a part corresponding to the ordinary goose-neck or snake head of the so-called side filling stop motion to the end that one actuator lever will be effective to stop the loom through the side filling and also warp stop motions.

Certain looms are so constructed as to have a cloth supporting board which extends far enough back from the breast beam as to have very little clearance with the lay when the latter is in its extreme forward position, thus rendering difficult the placing of the ordinary side fork lever between the cloth board and the lay. It is a further object of my present invention to provide a side stop motion with an actuating member having a regular vibrating motion, said part passing through a portion of the lay and being out of the range of the cloth board so as to permit the latter to be as close to the lay as desired.

It is a further object of my present invention to combine the filling and warp stop motions in such a way that the filling stop motion shall be effective to stop the loom on alternate picks while the warp stop motion shall be effective to stop the loom on the intervening picks.

With these and other objects in view which will appear as the description proceeds, my invention resides in the combination and arrangement of parts hereinafter described and set forth in the claims.

In the accompanying drawings, wherein I have shown a convenient embodiment of my invention,

Fig. 1 is a vertical section taken through a loom having my invention applied thereto,

Fig. 2 is a top plan view taken in the direction of arrow 2, Fig. 1,

Fig. 3 is an enlarged detail side elevation of the actuating mechanism for the combined warp and filling stop motions,

Fig. 4 is an enlarged detail top plan view taken in the direction of arrow 4, Fig. 1, and

Fig. 5 is a vertical section on line 5—5 of Fig. 4.

Referring to Figs. 1, 2 and 3 I have shown a loom side 10 having in the lower portion thereof a constantly rotating driving shaft 11 to which is secured a cam 12. Said shaft has a complete revolution in two picks of the loom and the cam cooperates with a cam lever 13 fulcrumed at 14 and adjustably connected to an upright rod 15.

The head for actuating part of the warp stop motion includes a supporting bracket 16 on which is adjustably mounted the frame 17 in the upper portion of which is secured a stud 18. Rocking freely on said stud is the lever 19 adjustably connected to the upper end of rod 15. Hook 20 is formed on the lever 19 to cooperate with a dog 21 pivotally mounted on the lower end of lever 22 also freely pivoted on the stud 18.

A plurality of non-circular detector rods 23 are connected together by arms 24 and link 25 to a driving rod 26. The upper ends of said driving rod extends through a stud 27 carried by the lever 19 and the lower end of said rod is pivoted on an arm 28 extending from the left hand link 24 as shown in Fig. 3. The upper end of the rod is free to slide through the stud 27 and a compression spring 29 is interposed between said stud and a collar 30 adjustably held on the rod.

As the shaft 11 rotates the lever 19 will be rocked first in one direction and then in the other around the stud 18 so that the spring 29 will be moved downwardly when the lever rocks in a left hand direction and the rod 26 will be moved upwardly by engagement of stud 27 with nut 31 on said rod when the lever moves in a right hand direction as viewed in Fig. 3. Such motion of the rod is communicated to the link 25 and arms 24 to rock the detector rods 23. One of the arms 24 is formed with an extension to which is secured

a lifting pin 32 which as shown in Fig. 3 is designed to lie under and support the dog 21, the right hand end of the dog being weighted so that the same will normally rest on the pin 32. When the detector rods are free to oscillate the pin 32 will move upwardly as the hook 20 approaches the dog 21 and moves said dog out of the path of the hook, but when free movement of the non-circular rods 23 is resisted by a fallen drop wire D the arms 24 will be held against swinging movement and the pin 32 will be in down position so that the dog 21 will remain in the path of the hook 20. As the lever 19 moves in a left hand direction as viewed in Fig. 3 the dog and hook will engage each other and the lever 22 will be given a left hand movement to effect loom stoppage by mechanism to be described. The matter thus far described is substantially the same as that shown in the aforesaid patents to Holmes and myself and forms no part of the present invention except as to the construction of the upper end of the lever 22.

A filling stop motion comprises a stand 40 fixed to the loom frame and having slidably mounted therein a fork carrying member 41 to the rear end of which is pivotally mounted the filling fork 42. The lay L is provided with a slot 43 in the upper surface thereof through which extends the forward end of a rod 44 the rear end of which is connected to the oscillating lever 19 at 45. Said rod is supported by a bracket B and has the front end thereof bent upwardly as at 46 and lies under the sliding member 41 as shown more particularly in Figs. 4 and 5. The forward end of the fork is provided with a loop 47 which is normally in the path of the upturned end 46 of rod 44. The sliding member 41 is provided with a projection 48 which lies behind the finger 49 carried on a knock-off lever 50 pivoted to a stand 51 held on the loom frame. Said lever 50 has a forwardly extending arm 52 which projects through a slot 53 in shipper rod 54 extending along the front of the loom substantially parallel to the breast beam 55. The shipper rod 54 may be of the form shown in Patent No. 884,614 and is effective when moved in the direction of arrow A Fig. 4 to stop the loom, movement in the opposite direction applying the driving power to the loom to cause operation of the same.

A control rod 56 is pivotally connected at the rear end thereof as at 57 to the upper end of lever 22 and the forward end of said rod 56 is adjustably connected to the lever 50 as at 58. The breast beam may be provided with a cloth supporting rear extension 59 which will lie very close to the front portion of lay L when the latter is in its extreme forward position as shown in Fig. 1.

In operation the cam will cause the lever 19 to oscillate as previously described, the effect of which is to cause the rod 44 to move

back and forth with the hook 20. So long as weft is present the fork 42 will be swung on its pivot to move the loop 47 above the end 46 of the rod 44 and as the latter moves forwardly the slide member 41 will remain at rest. When the filling is broken, however, the fork 42 will not be rocked on its pivot and as the upturned end 46 advances it will engage the loop 47 and move the sliding member 41 forwardly to cause the projection 48 to move the finger 49 to the dotted line position shown in Fig. 4. This movement is accompanied by a movement of the shipper rod in the direction of arrow A to stop the loom. As inspection of the cam will show that when it is in the position shown in Fig. 1 the hook 20 will be completing its idle stroke while the rod 44 will be completing its working stroke so that should the loom be stopped because of faulty filling the lever 22 and the rod 56 will be free to move without interference on the part of the hook. Also it will be seen that on the next pick the hook 20 will have a rocking stroke while the rod 44 will have a return or idle stroke so that if the loom should be stopped on this pick by a warp fault the rod 56 can move the lever 50 while the rod 44 is on its idle or inoperative stroke. By having the filling and warp stop motions operate on different picks I avoid any possibility of one interfering with the free action of the other.

It will be seen that the spring 29 is effective to give a yielding drive for the warp stop motion when the actuator lever 19 rocks in one direction and that the substantially horizontal rod 44 which cooperates with the filling stop motion is driven positively from the actuator lever on alternate oscillations of the actuating lever.

From the foregoing it will be seen that I have provided a combined filling and warp stop motion wherein the power for stopping the loom due to the instrumentality of either of the motions is derived from a single rocking lever and that the connections are such that said lever has a rocking stroke in one direction on one pick for one of the motions and has a rocking stroke in the other direction on the following pick for the other motion, so that there is no possibility of confusion or interference between the motions in their respective operations to stop the loom. It will further be seen that the rod 44 oscillates through a slot formed in the top of the lay and for this reason it is unnecessary to provide room between the extension 59 of the breast beam and the lay for the usual side filling stop motion operating lever.

It is a matter of practical necessity to have the filling stop motion operate when the lay is in its extreme forward position and under many conditions it is preferable to have the warp stop motion operate to stop the loom at the same part of the pick so that the cam may be made symmetrical to permit reversal of

the same on the driving of the bottom shaft. It will be understood, however, that this relation between the desirable times for stopping the loom is not essential, it being permissible to stop the loom from the warp stop motion at times other than those when the lay will be in its extreme forward position.

Having thus described my invention it will be apparent that changes and modifications may be made therein by those skilled in the art without departing from the spirit and scope of the invention and I do not wish to be limited to the details herein disclosed, but what I claim is:

15 1. In loom stopping mechanism, a warp stop motion, a filling stop motion, an actuating lever, means to give said lever operative movements in opposite directions, means under control of the warp to render said lever effective to stop the loom when said lever rocks in one direction and there is a fault in the warp, and additional means under control of the filling to render said lever effective to stop the loom when said lever rocks in the 25 other direction and there is a fault in the filling.

2. In loom stopping mechanism, a warp stop motion, a filling stop motion, an actuating lever movable first in one direction and then in the other and having such movements in regular sequence, means under control of the warp to render said lever effective to stop the loom when there is a fault in the warp and said lever is rocking in one direction, and 35 additional means under control of the filling to render said lever effective to stop the loom when the same rocks in the opposite direction and there is a fault in the filling.

3. In loom stopping mechanism, shipping 40 mechanism, a warp stop motion, a filling stop motion, an actuator lever having regular movements in opposite directions and having a cycle of movements which requires two picks of the loom for its completion, and 45 means to connect said lever when the same rocks in one direction with the shipping mechanism to stop the loom when there is a fault in the warp, and means to connect said lever when the same rocks in the opposite direction to the shipper mechanism to stop the loom when there is a fault in the filling.

4. In loom stopping mechanism, a shipper 55 mechanism movable in one direction to stop the loom, a warp stop motion, a filling stop motion, an actuating lever and having a cycle of movements which requires two picks of the loom for its completion having normal movements in opposite directions and associated with one of said motions, means effective when said lever rocks in one direction to move the shipping mechanism to stop the loom when there is a fault in the warp, and additional means effective when said actuating lever rocks in the opposite direction to

actuate the shipping mechanism to stop the loom when there is a fault in the filling.

5. In loom stopping mechanism, a warp stop motion, a filling stop motion, a shipper handle effective when moved in one direction to stop the loom, an actuating lever and having a cycle of movements which requires two picks of the loom for its completion having normal periodic movements in opposite directions, and means whereby said actuating lever will cooperate with either stop motion and move the shipper handle to stop the loom, said actuating lever moving in one direction to cooperate with the warp stop motion and moving in the other direction to cooperate with the filling stop motion.

6. In stopping mechanism for looms, a warp stop motion, a filling stop motion, a shipper member to be moved in one direction to stop the loom, and an actuating lever and having a cycle of movements which requires two picks of the loom for its completion having regular normal movements in opposite directions, said stop motions to be operatively related to the actuating lever one at a time and causing said actuating lever to produce a stopping movement of the shipper member irrespective of the direction in which the actuating lever is rocking.

7. In loom stopping mechanism, a warp stop motion, a filling stop motion, an actuating lever and having a cycle of movements which requires two picks of the loom for its completion having regular movements in opposite directions and having a movement which is idle with respect to one of said motions while having a working stroke with respect to the other motion, a shipper member to stop the loom, and connections from said actuating lever whereby either stop motion may cause said actuating lever to effect stopping movement of the member in whichever direction the lever is rocking.

8. In stopping mechanism for looms, a driving unit, a warp stop motion, a filling stop motion, a connection from the driving unit to the warp stop motion to actuate the latter, and a second connection between the warp stop motion and the filling stop motion, said second connection transmitting driving power to the filling stop motion from the driving unit which is transmitted through the first connection to the warp stop motion.

9. In a stopping mechanism for looms, a driving unit including a rotating cam, a warp stop motion, a filling stop motion, connections interposed between the cam of the driving unit and the warp stop motion to actuate the latter to stop the loom upon a fault in the warp, a second connection operatively connecting the warp stop motion and the filling stop motion and communicating driving force derived from the driving unit and transmitted through the warp stop motion,

the filling stop motion otherwise being independent of the cam.

10. In stopping mechanism for a loom, a driving unit having a cycle of operation which requires two picks of the loom to be completed, a warp stop motion, a filling stop motion, connections from the driving unit to the warp stop motion to actuate the warp stop motion to have a loom stopping movement on one pick of the cycle, and connections between the warp stop motion and the filling stop motion to transmit power derived from the driving unit and transmitted through the warp stop motion and effective to actuate the filling stop motion to stop the loom on the other pick of the cycle of the driving unit when there is a fault in the filling.

11. In loom stopping mechanism, a driving unit requiring two picks of the loom for a complete cycle of said unit, a warp stop motion, an actuator lever forming an essential part of the warp stop motion, a connection between the driving unit and the actuating lever to give the latter a working stroke on one pick of the cycle of the driving unit, a filling stop motion, a connection between the actuating lever and the filling motion, said second connection transmitting a driving force to the filling stop motion which is derived from the driving unit and communicated through the warp stop motion to stop the loom through the filling stop motion on the other pick of the cycle of the driving unit when there is a fault in the filling.

12. In stopping mechanism for a loom, a driving unit having a cycle of operation which requires two picks of the loom for its completion, a warp stop motion, an actuating lever forming an essential part of the warp stop motion, connections between the driving unit and the actuating lever to give said actuating lever a working stroke with respect to the warp stop motion on one pick of the cycle and a non-working stroke with respect to the warp stop motion on the other pick of the cycle of the driving unit, a filling stop motion, and connections between the actuating lever and the filling stop motion effective to actuate the latter by a force transmitted through the warp stop motion to stop the loom when the actuating lever has a non-working stroke relatively to the warp stop motion upon occurrence of fault in the weft.

13. In stopping mechanism for a loom, a driving unit having a cycle of operations requiring two picks of the loom for its completion, a warp stop motion, a filling stop motion, connections between said stop motions and the driving unit whereby the latter is effective to act through the warp stop motion to stop the loom upon only one pick of the cycle when there is a fault in the warp and through the filling stop motion on the other pick of the cycle when there is a fault in the filling.

14. In a stopping motion for looms, a driv-

ing unit having a cycle of movement which requires two picks of the loom for its completion, a warp stop motion, an actuator lever forming part of the warp stop motion, a filling stop motion, a connection between the driving unit and the actuator lever to move the latter in one direction on one pick of the cycle of the unit and in the other direction on the other pick of the cycle, said driving unit being effective to stop the loom through operation of the warp stop motion upon fault in the warp when the actuator lever moves in one direction and being effective to stop the loom through the filling stop motion upon fault in the filling when the actuator lever moves in the other direction.

15. In a stopping mechanism for looms, a filling stop motion, a warp stop motion, an actuating lever which oscillates so as to move first in one direction and then in the other, means including a yielding element effective to give the warp stop motion a detecting movement, said means being actuated by the lever when the latter moves in one direction, and means to transmit a positive driving force from the actuating lever to the filling stop motion when said actuating lever moves in the other direction.

16. In a stopping mechanism for looms, a filling stop motion, a warp stop motion, an actuator lever forming part of the warp stop and having a working stroke relatively to the warp stop motion and having a non-working stroke relatively to the warp stop motion but operative with respect to the filling stop motion, means defining a yielding connection between the actuator lever and the warp stop motion to give the latter a detecting movement when the actuator lever has a working stroke relatively to the warp stop motion, and means defining a positive connection between the actuator lever and the filling stop motion to give the latter a detecting movement when the actuator lever has the non-working stroke relatively to the warp stop motion.

17. In loom stopping mechanism, a warp stop motion, a filling stop motion, a regularly moving actuator lever for both of said motions, means under control of the warp to render said lever effective when a warp fault occurs to stop said loom on an alternate pick only of the loom, and additional means under control of the filling to render said lever effective to stop the loom on an intermediate pick of the loom when there is a fault in the filling.

In testimony whereof I have hereunto affixed my signature.

JOHN REGAN.
